UNITED STATES PATENT OFFICE.

ROBERT R. CANAVELLO, OF BROOKLYN, NEW YORK.

CONTAINER.

Application filed September 19, 1924. Serial No. 738,600.

Loose face-powder is more desirable for use than the powder compact, because certain ingredients added in the compacting process to the powder destroy its delicate texture and purity. Compacts are not standard in size; hence a refill cake may not fit a particular box. Not all powders are obtainable in compact form. Even the assumed convenience offered by the compact is not as great as generally supposed, for in use, being brittle, compacts break easily—many are broken in shipping—and once broken, they crumble into a coarse undesirable powder.

Loose powder spills when carried in an ordinary vanity box. This invention has for an object to provide a container for face-powder or other similar substances that is powder-tight, of the vanity type in which loose powder may safely be carried without spilling and consequent damage to clothes, or (in a larger form) as a novel container in which face-powder may be generally marketed.

Loose powder has a tendency to pack, especially when picked up from an open container by pressing a puff upon it. To avoid packing users often shake a small quantity of powder from such a container into its cover, where it is lightly and evenly taken up upon the puff. A further object of this invention is to provide a bowl, in conjunction with the container element, from which powder may be picked up on a puff, after being transferred by other means from the container through an opening formed by cutting away a preferably crescent-shaped portion from the edge of the bowl. The bowl prevents waste, as just the desired quantity of powder intended for immediate use is transferred to it; and the extravagance is avoided of overloading the puff, as in the case of ordinary open containers, which necessitates dusting off and wasting the superfluous powder thus applied to the face.

The powder in the container forming the subject-matter of the present invention always retains its desirable lightness, because the puff never comes into direct contact with it. As the bowl helps in the even distribution of it on the puff, the powder is consequently applied more smoothly and economically to the face.

A further object is to provide a container from which practically every bit of powder may be removed. This distinguishing fea-

ture is not found in any loose-powder vanity box of which I am aware, the powder usually being obtained through an opening or openings in the center of the box. As in the present container the opening occurs at its peripheral edge, it may be completely emptied of its contents. To attain this object with the maximum facility I provide a yieldable wall or chute of springy material which is fixed to the bottom of the box, extends upward snugly fitting and slidable at its sides against the walls of the box, normally bearing against the edge of the bowl at the point where a portion has been cut away, and extending to a point above the bowl at its free end. Upon tilting the box toward the chute, the powder is shifted upon the chute and, when the chute is pressed away from the bowl, slides down it through the gap thus made and into a spoon-shaped hollow formed in its free end above the bowl. When released, the chute springs back of its own accord against the lip of the bowl, closing the box and flipping the powder contained in its spoon-shaped portion onto the bowl, ready to be picked up by a puff.

In the accompanying drawings I have illustrated a preferred embodiment of my invention.

Figure 1 is a plan view of a container embodying the invention, partly broken away; Fig. 2 is a section on the line 2—2 of Fig. 1;

Fig. 3 is a partial section on the line 2—2 of Fig. 1 showing the chute depressed;

Fig. 4 is a partial section on the line 2—2 of Fig. 1 showing the chute returned to closed position and discharging powder on the bowl; and,

Fig. 5 is a sectional view of a modified form with a hinged cover 7.

The powder is contained in a box 1, of any desired shape, but here shown round, that 100 being the form most generally used. Above the powder is a bowl 2, which may if desired be hinged as at 3, as shown in Fig. 5. At a convenient point, preferably opposite the hinge, a portion of the bowl is cut away to leave a space 4 between the edge of the bowl 2 and the wall of the box 1. Fixed to the bottom of the box is a false wall or chute 5, projecting upwardly through the space 4 and preferably spoon-shaped at its upper end 6 above the bowl. This is preferably set out from the wall of the box at the

bottom somewhat as shown, and is formed of a resilient material so as to be normally held against the edge of the bowl, keeping the container closed.

5 When it is desired to use some powder, the box is tilted toward the chute 5, which is drawn back from the bowl 2 toward the edge of the box 1 permitting powder to flow through the space 4 and fill the spoon-shaped portion of the chute 5, as shown in Fig. 3, which is then released, flipping the desired quantity of powder into the bowl, and closing the receptacle, as shown in Fig. 4.

Provision may be made for ready access 15 to the container portion for refilling the same, as shown in Fig. 5, the container portion 1 being hinged, as at 3. In a box for marketing powder the refilling feature is usually undesirable, in which case the box 20 may be sealed after filling, so that the only access to the powder is through the opening 4, by depressing the chute 5.

Having now described my invention what I claim and desire to secure by Letters Patent is:

25 1. The combination comprising a powder receptacle, a mixing bowl serving as a cover therefor, an opening adjacent the junction of the receptacle and bowl, and a member normally closing said opening and adapted when actuated to throw a portion of powder onto the bowl.

30 2. The combination comprising a powder receptacle, a mixing bowl serving as a cover therefor, an opening through said bowl, and a member spoon-shaped at one end normally closing said opening and adapted when actuated to throw a portion of powder onto the bowl.

35 40 3. The combination comprising a powder receptacle, a mixing bowl disposed above

45 said receptacle, an opening through said bowl, and a plate extending through said opening and normally bearing yieldably against said bowl.

4. The combination comprising a powder receptacle, a mixing bowl disposed above said receptacle, an opening at the junction of the receptacle and bowl, and a plate fixed to the bottom of the receptacle and extending 50 angularly upward through said opening and normally bearing yieldably against said bowl.

5. The combination comprising a powder receptacle, a mixing bowl associated therewith, and resilient means for throwing a portion of powder from the receptacle onto the bowl.

55 6. The combination comprising a powder receptacle, a mixing bowl associated therewith, the said mixing bowl having a substantially rigid bottom adapted to form a cover for the receptacle, an opening through said bottom, the said opening being located between the center and the peripheral edge 60 of the bottom, and means for throwing a portion of powder from the receptacle onto the bowl.

7. The combination comprising a powder receptacle, a mixing bowl associated therewith having a bottom adapted to form a cover for the receptacle, an outlet opening extending through said cover, and resilient means extending below the surface of the powder and projecting through said opening for throwing a portion of powder from the receptacle onto the bowl, and acting normally to keep said receptacle outlet closed.

75 In testimony whereof I have signed my name to this specification.

ROBERT R. CANAVELLO.
